(57) **CLAIM**

The ornamental design for “buckle”, substantially as shown and described.

DESCRIPTION

FIG. 1 is a front view of a buckle showing our new design;

FIG. 2 is a rear view thereof;

FIG. 3 is a top plan view thereof;

FIG. 4 is a bottom view thereof;

FIG. 5 is a right side view thereof;

FIG. 6 is a cross sectional view along the line VI—VI of FIG. 1;

FIG. 7 is a front view of a male body of the buckle;

FIG. 8 is a rear view thereof;

FIG. 9 is a top plan view thereof;

FIG. 10 is a bottom view thereof;

FIG. 11 is a right side view thereof;

FIG. 12 is a cross sectional view along the line XII—XII of FIG. 7;

FIG. 13 is a front view of a female body of the buckle;

FIG. 14 is a top plan view thereof;

FIG. 15 is a bottom view thereof;

FIG. 16 is a right side view thereof;

FIG. 17 is a cross sectional view along the line XVII—XVII of FIG. 13;

FIG. 18 is a cross sectional view along the line XVIII—XVIII of FIG. 16;

FIG. 19 is a perspective view of the male and female bodies of the buckle; and,

FIG. 20 is a perspective view of the buckle in coupled position.

Left side views of the buckle, and the male and female bodies are omitted because they are symmetrical with their right side views. Additionally, a rear view of the female body is omitted because it is the same as the front view thereof.
